MELBOURNE KEITH DUNHAM, OF CHICAGO, ILLINOIS.

CUTTING-TORCH.

1,303,178.

Specification of Letters Patent.

Patented May 6, 1919.

Application filed March 4, 1919. Serial No. 280,527.

To all whom it may concern:

Be it known that I, MELBOURNE KEITH DUNHAM, a citizen of the United States, and a resident of Chicago, in the county of Cook and State of Illinois, have invented 5 certain new and useful Improvements in Cutting-Torches, of which the following is a specification.

This invention is an improved cutting 10 torch of that general type which is adapted to apply a jet of heating flame to the material to be cut, to heat said material to the necessary or desired high temperature, and to deliver oxygen or a gaseous oxidizing 15 mixture to the heated material to oxidize it and remove the oxid to produce a cut, as is well understood by those skilled in the art. In common practice, the heating flame, which may be a mixture of oxygen and acet- 20 ylene, or hydrogen, is applied before the oxidizing jet and means are provided for quickly opening and closing the supply to the oxidizing jet at the beginning and end of the cutting operation. Such means com- 25 monly includes a valve openable against a spring by means of a valve lever so positioned in respect to the handle of the torch that it may be easily operated by the thumb or fingers of the hand which grasps the 30 handle and carries the torch.

The novel features of my invention reside primarily in the means employed for operating and controlling the cutting oxygen valve. The main object of my invention is 35 to provide a simple, easily operated and inexpensive construction in which a compar- -tively strong spring may be used to no- mally hold the valve to its seat but in which the valve may be easily opened against the 40 action of the spring, and may be automatically locked in open position or easily re- leased to permit closing. In my improved construction, I provide a valve operating lever pivotally mounted at or adjacent to 45 one end of the handle and co-acting with the valve stem at a short distance from the pivotal point. The swinging end of the lever preferably terminates adjacent to the oppo- site end of the handle and, in swinging, 50 slides along a pivoted locking member ex- tends substantially at right angles to the general direction of the handle. The locking member is so designed that its normal engagement with the valve lever will pre- 55 vent the return movement of the latter to closed valve position but the locking mem-

ber is conveniently positioned and easily op- erated to release the valve lever at will. This locking device serves merely to relieve such strain on the hand of the operator as 60 might result, were it necessary for him to hold the valve lever in depressed position against the action of the spring while con- ducting a cutting operation for a consider- able length of time. 65

I preferably form the handle or grip member of a piece of tubing encircling the oxygen and acetylene or other gas conduits leading to the head. This tubing at its op- posite ends engages with separate metal 70 blocks or collars encircling or secured to the conduits and as an important feature of my invention I form these blocks or collars with lugs or other pivotal connections for the valve lever and the lever locking member so 75 that firm and rigid supports are provided for these pivoted members beyond the ends of the tube and without engagement with or connection to the thin wall of the latter. This also permits the valve lever to be locked 80 at a point a considerable distance from the fulcrum and valve stem where the strain on the parts is therefore comparatively small.

In the accompanying drawing I have 85 illustrated one of many possible embodiments of my invention and in connection with merely one of many forms of cutting torch with which my invention may be em- ployed.

In these drawings: 90
Figure 1 is a side elevation of a complete torch, and

Fig. 2 is a top plan view of the handle portion on a larger scale, portions thereof being broken away. 95

In the particular form of cutting torch illustrated, there is provided a block or cast- 100 ing 10, having a pair of bosses 11, and 12 to which acetylene and oxygen conduits may be connected. At the opposite side of the block is a transverse flange 13, into which three separate conduits 14, 15, and 16 may be rigidly secured. The block has a pas- 105 sage therethrough connecting the conduit 16 with the boss 11, whereby the acetylene may be delivered to said conduit. The flow of the acetylene may be controlled by a needle valve 17 or other controlling means. The boss 12 has a passage 18 leading to the central conduit 15, the flow through this con- 110 duit being controlled by a needle valve 19 or other controlling means. The boss 12 also

has a passage 20 leading to a valve chamber 21 and from which the oxygen may flow to the conduit 14 when the valve 22 is opened against the action of the spring. The valve 5 22 has a stem 23 extending through a suitable packing to the exterior of the block and into operating relationship with the valve lever 24. This valve lever is shown as pivoted to a lug 25 on the rear end of the block 10 or casting 10, adjacent to the valve stem. The free or swinging end of the lever extends in the general direction of the conduits of the torch and when pressed toward said conduits acts against the valve stem 23 10 to open the valve against the pressure of its spring.

The handle of the torch is formed of a piece of tubing 26 encircling the rear portions of the conduits and spaced therefrom. 20 As shown, the rear end of this tubular handle member telescopes on to a cylindrical portion 27 of the block 10 and it may be secured to the latter by screws 28, or in any other suitable manner. At the opposite end 25 of the tubular handle 26, there is employed a second block or collar 29 having separate openings therethrough for the three conduits 14, 15, and 16 and also having a reduced portion telescoping into the end of 30 the tube 26. The tube is thus held rigid in respect to the conduits but spaced therefrom.

The valve lever 24 lies adjacent to but normally spaced slightly from this tubular 35 handle and terminates adjacent to the forward end of the latter. The collar or block 29 is provided with a lug 30, to which is pivoted a locking member 31. This is shown as extending through an aperture 32 in the 40 valve lever and as being provided with a recess 33 in one side thereof, which may receive a portion of the valve lever at one end of the aperture 32. A spring 34 normally presses the locking member 31 in such a direction as to hold it with the recessed or 45 notched side against the valve lever so that as the valve lever is depressed or squeezed toward the handle, it will slide down the side of the locking member until it comes 50 opposite the recess 33 and the locking member will then be swung into operative or retaining position. Although I have shown the locking member with only a single recess in the side thereof, it will of course be 55 evident that a larger number of recesses or notches may be provided, if it is desired to hold the valve open to other than one predetermined extent. Merely to prevent the free end of the valve lever from swinging 60 away from the handle to an undesired extent when the oxygen valve is closed, the locking member 31 may be provided with a head 34 which cannot pass through the recess 32 but which may be unscrewed and 65 removed in case it is desired to swing the

lever 24 outwardly beyond the normal closed valve position.

I have shown the three conduits 14, 15, and 16 leading to a head 35 to which a tip 36 is detachably secured by a union nut 37. 70 I have not shown the various passages through the head and tip or through the block 10 as the particular arrangement of said passages forms no portion of my present invention and may be in accordance 75 with any design preferred by the manufacturer.

It will be understood that the oxygen and acetylene flowing through the conduits 15 and 16 mixes in the head to form the heating 80 flame mixture, while the oxygen supplied through the conduit 14 may be controlled by the valve lever when it is desired to begin or end the cutting operation. This oxygen ordinarily is delivered through a separate 85 passage in the tip from that in which the heating mixture flows.

Having thus described my invention what I claim as new and desire to secure by Letters Patent is:

1. A cutting torch having a plurality of gas conduits, a tubular handle encircling said conduits, separate members at each end of said tubular member for spacing the latter from said conduits and holding it 95 rigid in respect to them, a valve for controlling the flow through one of said conduits, a valve lever pivoted to one of said members, and a locking or retaining element pivoted to the other of said members 100 and engaging with the free end of said valve lever.

2. A cutting torch having a tubular handle or grip member, a plurality of conduits extending therethrough, spacing members at each end of said tubular handle for holding it rigid in respect to said conduits, a valve for controlling the flow of gas through one of said conduits, a valve lever pivoted to one of said members and extending lengthwise of said handle and of greater length than said handle, and means carried by the other of said members and movable in the direction of the length of the handle for engaging with the free end of said lever to 110 lock it in open valve position.

3. A cutting torch having a valve block, a head, a plurality of conduits connecting said block and head, a spring pressed valve within said block for controlling the flow 120 through one of said conduits, a lever pivoted to said block and extending approximately parallel to said conduits toward said head, and a pivoted member extending approximately at right angles to the general direction of the length of said conduits adjacent to the free end of said valve lever for engaging with the latter to hold the valve lever in open valve position.

4. A cutting torch having a head, a plu- 130

rality of substantially parallel gas conduits leading thereto, a spring pressed valve for controlling one of said conduits, a pivoted valve lever extending in the general direction 5 of the length of said conduits and having its free end movable toward said conduits and provided with an aperture therethrough, and a retainer extending approximately at right angles to the general direction of said 10 lever through the aperture of the latter and

having a recess for receiving and retaining the valve lever and holding it in open valve position upon the movement of the free end of the lever toward said conduits to a pre-determined position.

15

Signed at Chicago in the county of Cook and State of Ill. this 1st day of March A. D. 1919.

MELBOURNE KEITH DUNHAM.
